UNITED STATES PATENT OFFICE.

RUDOLPH COOPERSMITH, OF ST. LOUIS, MISSOURI.

CANVAS-COVERED COT AND PROCESS OF STRETCHING THE CANVAS THEREON.

Application filed August 15, 1921. Serial No. 492,346.

To all whom it may concern:

Be it known that I, RUDOLPH COOPERSMITH, a citizen of the United States, and a resident of the city of St. Louis, in the State of Missouri, have invented a new and useful Improvement in Canvas-Covered Cots and Processes of Stretching the Canvas Thereon, of which the following is a specification.

10 This invention relates principally to folding canvas covered cots having metallic frames, and more particularly to the manner of securing the canvas to the frame and to the process of stretching said canvas thereon.

One of the principal objects of the present invention is to provide a metallic cot-frame with a stretched canvas covering. Another object is to obtain a uniform 20 stretching of the canvas covering throughout its entire length. Another object is to distribute the pulling strains of the stretched canvas along the entire length thereof and to prevent tearing and ripping 25 of the canvas at its point of attachment to said frame. Another object is to devise a process of stretching the canvas on the cot-frame that will place the canvas under constant tension after it is secured to said 30 frame. Other objects are to simplify the construction and to reduce the cost of manufacturing such cots.

The invention consists principally in a metallic cot having a stretched canvas covering secured directly thereto. It also consists in the improved means for securing the canvas to the frame, in the process of distorting the frame to set up a strain therein and then securing the canvas covering thereto, whereby said covering is stretched or made tense upon the frame. The invention further consists in the parts and in the combinations and arrangements of parts hereinafter described and claimed.

45 In the accompanying drawings, which form part of this specification, and wherein like symbols refer to like parts wherever they occur—

Fig. 1 is a plan view of the cot embodying my invention;

Fig. 2 is a side elevation thereof;

Fig. 3 is a cross-sectional view on the line 3—3 in Fig. 1, showing the cot and leg frames as initially formed;

55 Fig. 4 is a similar section showing the cot

and leg frames after the canvas covering has been secured in position; and

Fig. 5 is an enlarged detailed cross-section through one of the side rails of the cot-frame on the line 5—5 in Fig. 1, showing the manner of attaching the canvas covering thereto.

The cot shown in the accompanying drawings comprises a main bed or cot-frame formed of an intermediate section I and 65 duplicate foldable head and foot sections H and F, respectively, said intermediate, head and foot sections being provided with a one-piece covering of canvas duck or like material C.

70 The intermediate section I of the bed frame comprises a pair of spaced angle-iron side rails 1 arranged with their vertical flanges up and with their horizontal flanges facing each other.

75 The duplicate head and foot sections H and F comprise angle-iron side rails 2 arranged with their vertical flanges up and with their horizontal flanges facing each other in a manner corresponding to the 80 flanges of the angle-iron side rails 1 of the intermediate section I. The side rails 2 of the head and foot sections are connected at their outer ends by angle-irons 4, which constitute the end rails of the cot-frame; and in 85 the angles formed by said side and end rails are corner braces 5.

The inner ends of the angle-iron side rails 2 of the end sections H and F fit within the adjacent end portions of the angle-iron side 90 rails 1 of the intermediate section I. The horizontal flanges of the side rails of the end sections rest upon the horizontal flanges of the side rails 1 of the intermediate section, and said end sections are pivotally secured 95 to the opposite ends of the intermediate sections by means of pivots 6. The pivots 6 pass through the lapped vertical flanges of the side rails of the end and intermediate sections, whereby said end sections are foldable upon said intermediate sections.

100 The foot section is held in a horizontal position by means of the horizontal flanges of the side rails of the intermediate sections. The head section is held in an inclined position by the upwardly inclined end portions 7 of the side rails 1 of the intermediate section.

105 The cot-frame is supported by a pair of foldable leg frames L. Each frame comprises a pair of upright angle-iron legs 8 110

- arranged with one flange facing inwardly. The legs 8 of each frame are connected at points intermediate their ends by a horizontally disposed angle-iron cross-member.
- 5 9. The frames are strengthened at the angles between the legs 8 and cross-members 9 by corner braces 10. The outer flanges of the legs of one frame face the outer flanges of the legs of the other frame and said flanges are pivotally secured at their upper ends, as at 11, to the outer faces of the vertical flanges of the side rails of the intermediate sections, whereby said legs are adapted to fold underneath the cot-frame.
- 15 10. The side and end marginal portions of the canvas covering C are formed with doubled-over portions in the form of hems 12. Positioned within these hems are strips of metal 13. The covering is secured to the upper surfaces of the horizontal flanges of the side and end rails of the cot-frame by means of stove bolts 14, which pass through aligned holes in said horizontal flanges and in the securing strips. The use of an intermediate strip and two end strips is required on each side of the frame to permit folding of the end sections, a sufficient space being left between the adjacent ends of the end and intermediate strips for this purpose. The use of the strips 13 for securing the side and end margins of the canvas covering to the cot-frame results in an even distribution of the pulling strains of the canvas and prevents tearing of the canvas at the securing bolts when the canvas is drawn tight.
- 20 25 30 35 40 45 50 55 60 65 The process of assembling the cot is as follows: The cot-frame is initially made of a width greater than is desired for the finished cot; and the leg-frames are also made of a width that will permit the upper ends of the outermost flanges of the legs to lap the outer flanges of the side rails of the cot, or, if desired, the legs may be set at an angle, as shown in Fig. 3, whereby the width of the base of the frame is approximately that desired for the finished cot and the width of the upper end corresponds to the initial width of the cot-frame. The leg-frames are then pivotally secured to the side rails of the cot-frame. The side rails are then drawn inwardly towards each other, preferably by means of clamps, a distance that will permit the bolt holes in the securing strips 12 in the side hems 13 of the canvas covering to register with the bolt holes in the side rails. The canvas covering is then secured to the side and end rails of the cot-frame by means of the bolts 14. By reason of the connections between the leg-frames and the bed-frame, the action of drawing the side rails of the cot frame inwardly causes the upper ends of the legs to be drawn inwardly, thereby straining the cross-members 9 of the leg-frames and also the end rails 4, thereby causing said cross-

pieces and said end rails to bow downwardly. The pressure on the side rails is then released and the bowed cross-members and end rails tend to straighten, which action spreads apart the side rails thereby stretching the canvas therebetween. The distance that the side rails are permitted to spread depends on the strength of the canvas. The initial width of the canvas is such that with a maximum amount of stretching the cross-members of the leg-frames and the end members of the cot-frame will remain slightly bowed, thus placing the canvas under a constant state of tension.

Obviously, the hereinbefore described construction admits of considerable modification without departing from the invention and I do not wish to be limited to the exact form of cot shown and described.

I claim:

1. A cot comprising an open frame formed of connected side and end rails, a fabric covering therefor, the marginal portions of said covering being formed with hems, stiff reinforcing strips in said hems, and means disposed at intervals and passing through said strips and said side and end rails for securing said covering to the frame, and leg frames each comprising legs secured to the respective side rails, a single cross-member connecting said legs and adapted to be bowed to maintain tension in said covering, and braces extending obliquely from said legs to said cross-member.

2. A cot comprising an open frame formed of connected metallic side and end rails, a canvas covering therefor, the margins of said covering being formed with hems, metallic reinforcing strips in said hems, and means for securing the reinforced hem portions of the covering to the frame at intervals throughout its border, and leg frames each comprising legs secured to the respective side rails, a single cross-member secured to said legs below the tops thereof and corner braces extending from the top portions of each of said legs to said cross-member, whereby the bowing of said leg frames downwardly prior to the fastening of the canvas covering maintains said canvas under tension.

3. The process of stretching canvas on a cot-frame comprising connected metallic side and end rails, which consists in drawing the side rails of the frame closer together throughout their length than is desired for the finished frame, whereby the end rails are bowed downwardly slightly, securing the canvas to said side rails, and then releasing said side rails, whereby the tendency of the bowed end rails to straighten spreads said side rails and stretches the canvas therebetween.

4. The process of stretching canvas on a cot-frame comprising an open frame formed

of side and end rails and supported by legs secured to the opposite sides of said frame, the legs at each end being connected together by a single metallic cross-member 5 and both connected also to said cross-member by oblique braces, which consists in drawing the side rails of said frame closer together throughout their length than is desired for the finished frame, whereby the 10 end rails of the frame and the cross-mem-

bers connecting the legs are bowed downwardly slightly, securing the canvas to the side rails and then releasing said side rails, whereby the tendency of the bowed end rails and the cross-members to straighten spreads 15 said side rails and stretches the canvas therebetween.

Signed at St. Louis, Missouri, this 11th day of August, 1921.

RUDOLPH COOPERSMITH.
